UNITED STATES PATENT OFFICE.

GEORGE B. ADAMS, OF NEWARK, ASSIGNOR OF ONE-HALF HIS RIGHT TO
PHILIP H. RYAN, OF EAST ORANGE, NEW JERSEY.

IMPROVEMENT IN TOYS.

Specification forming part of Letters Patent No. 146,157, dated January 6, 1874; application filed
December 12, 1873.

To all whom it may concern:

Be it known that I, GEORGE B. ADAMS, of the city of Newark, in the county of Essex and State of New Jersey, have invented certain new and useful Improvements in Toys; and I do hereby declare the following to be a full, clear, and exact description of the invention, such as will enable others skilled in the art to which it pertains to make and use it, reference being had to the accompanying drawings, which form part of this specification.

In the drawing hereto annexed, Figures 1 and 2 are transverse sectional views of a toy combining my improvements.

A is an ordinary ball having a hole in the center, in which is arranged a kaleidoscope, B, made in the usual manner. C is an elastic cord attached to the ball, which may or may not be used.

This invention consists in combining a kaleidoscope with an ordinary ball, made of wood or other suitable material, and supplied with an elastic cord, substantially as shown, thus combining with the ordinary "return ball" a

kaleidoscope; or the elastic cord may be dispensed with, if desired, and the ball be used by tossing it in the air, or rolling it about the floor or ground.

The kaleidoscope is inserted in the ball, as shown, and secured therein by cement or any other suitable fastening. The outer glass, a, may be protected by a suitable cap, b. The point of sight c need not be supplied with a glass.

What I claim as new, and desire to secure by Letters Patent, is—

As a new article of manufacture, a toy consisting of a kaleidoscope and ball, constructed and combined substantially as and for the purpose shown and described.

In testimony that I claim the foregoing I have hereunto set my hand this 11th day of December, 1873.

GEORGE B. ADAMS.
